They form stable protonates, i.e., pharmacologically acceptable acid addition salts, on acidification of the free base form with suitable pharmacologically acceptable acids, for example, hydrochloric, hydrobromic, sulfuric, phosphoric, nitric, acetic, propionic, palmitic, benzoic, salicylic, hexynoic, phenylbutyric, naphthoic, glycolic, succinic, nicotinic, tartaric, maleic, malic, pamoic, methanesulfonic, cyclohexanesulfonic, picric and lactic acids, and the like. 3. In the final step of Process D, a substituted or unsubstituted 6-phenyl-4H-s-triazolo[4,3-a][1,4]benzodiazepin-4-ol (I) produced in step (2) is tautomerized at the 4-position and selectively reduced at the 5-position, for example, by reacting a solution or suspension of an aforesaid 4-ol (I) with a dilute aqueous solution of an alkali metal hydroxide (e.g., sodium hydroxide or potassium hydroxide) at from about 25° C. to about 50° C. for a period of from about 1 to about 8 hours, to yield a corresponding 6-phenyl-4H-s-triazolo[4,3-a][1,4]benzodiazepin-4-one (IV).

(The preparation of a specific starting material of Formula C, namely, 4-(2-benzoyl-4-chlorophenyl)-5-methyl-4H-1,2,4-triazole-3-carboxaldehyde, is described in Parts A, B and C of Example 6, below.)

All of the novel compounds included with Formulae I, II, III and IV and the starting materials (A, B and C) therefor of the flow-sheet, above, can be isolated from their respective reaction mixtures by conventional means, for example, when a water-miscible solvent is used, by pouring the reaction mixture into water and separating the resulting precipitate by filtration or by extraction with water-immiscible solvents. Additional purification of the products can be accomplished by conventional means, for example, by elution chromatography from an adsorbent column with a suitable solvent such as acetone, ethyl acetate, ether, methylene chloride and Skellysolve B (hexanes), mixtures and combinations of these solvents; also by gradient elution chromatography from an adsorbent column with a suitable mixture of solvents, such as, methylene chloride Skellysolve B, acetone-Skellysolve B, and the like.

The novel compounds of Formulae I, II, III and IV and the pharmacologically acceptable acid addition salts thereof have sedative, hypnotic, anticonvulsant, tranquilizing and muscle relaxant effects in mammals and birds. Also, as feed additives for increasing growth rate and feed efficiency of livestock.

Sedative effects of the compound of this invention are shown by the following tests in mice:

45 Chimney test: [Med. Exp. 4, 145 (1961)]: The test determines the ability of mice to back up and out of a vertical glass cylinder within 30 seconds. At the effective dosage, 50 percent of the mice failed doing it.

50 Dish test: Mice in Petri dishes (10 cm. diameter, 5 cm. high, partially embedded in wood shavings), climb out in a very short time, when not treated. Mice remaining in the dish for more than 3 minutes indicates tranquilization. ED₅₀ equals the dose or test compound at which 50 percent of the mice remain in the dish.

55 Pedestal test: The untreated mouse leaves a standard pedestal in less than a minute to climb back to the floor of the standard mouse box. Tranquilized mice will stay on the pedestal for more than 1 minute.

Nicotine antagonism test: Mice in a group of six are injected with the test compound. Thirty minutes later the mice including control (untreated) mice are injected with nicotine salicylate (2 mg./kg.). The control mice show overstimulation, i.e., (1) running convulsions followed by (2) tonic extensor fits; followed by (3) death.

Antagonism to strychnine (as sulfate): The test consists in orally administering into groups of six mice

the test compound, and 30 minutes later 3 mg./kg. strychnine sulfate intraperitoneally. The survivors after 4 hours reflect the activity of the compound as a muscle relaxant and antispasmodic. A dosage of 3 mg./kg. of strychnine sulfate is routinely fatal to all the control mice.

The following compounds typical of this invention have (by intraperitoneal injection) ED₅₀ as shown in the table below.

DETAILED DESCRIPTION OF THE INVENTION

The following preparation and examples are illustrative of the processes and products of the present invention, but are not to be construed as limiting.

Preparation 1 8-chloro-1-methyl-6-phenyl-4H-s-triazolo[4,3-a][1,4]benzodiazepine (A)

- 25 Example 1
- A. 10-chloro-6-methyl-11b-phenyl-3H,11bH-oxazirino[3,2-d]-s-triazolo[4,3-a][1,4]benzodiazepine (III)
- B. 8-chloro-1-methyl-6-phenyl-4H-s-triazolo[4,3-a][1,4]benzodiazepine 5-oxide (II)
- A. 10-chloro-6-methyl-11b-phenyl-3H,11bH-oxazirino[3,2-d]-s-triazolo[4,3-a][1,4]benzodiazepine (III)
- A stirred solution of 1 g. (0.00324 mole) of 8-chloro-1-methyl-6-phenyl-4H-s-triazolo[4,3-a][1,4]benzodiazepine (A), (obtained as in Preparation 1) in absolute ethanol is cooled in an ice bath and mixed with 1.12 g. (0.00648 mole) of m-chloroperbenzoic acid. The mixture is kept in the ice bath for about 6 hours and then at room temperature for about 18 hours. It is then concentrated under vacuum; the residue is suspended in cold, dilute potassium carbonate solution and extracted with methylene chloride. The extract is washed with water, dried with potassium carbonate, concentrated under vacuum, chromatographed on a 100 g. column of silica gel and 50 ml. fractions collected. Fractions 1 through 48 are eluted with a mixture of 5 percent methanol and 95 percent ethyl acetate and fractions 49 through 70 with 10 percent methanol 90 percent ethyl acetate. The first compound is eluted in fractions 18 through 28 and crystallized from ethyl acetate to give 0.334 g. of 10-chloro-6-methyl-11b-phenyl-3H,11bH-oxazirino[3,2-d]-s-triazolo[4,3-a][1,4]benzodiazepine (III), melting at 169.5° to 170° C. (with decomposition) and 0.031 g. of the same compound melting at 168.5° to 169.5° C. (with decomposition). The analytical sample has a melting point of 167° to 167.5° C., ultraviolet (ethanol) end absorption with inflections at 235 m μ (ε=16,700), 263 m μ (ε=939), 269 m μ (ε=776), 275 m μ (ε=594) and 281 m μ (ε=523). The infrared, nuclear magnetic resonance and mass spectra support the proposed structure.

Anal. Calcd. for C₁₇H₁₃ClN₄O: C, 62.88; H, 4.03; Cl, 10.92; N, 17.25.
 Found: C, 62.95; H, 3.94; Cl, 11.05; N, 17.09.

The second compound is eluted from the column in

fractions 39 through 48 and crystallized from ethylacetate to give 0.105 g. of starting material, 8-chloro-1-methyl-6-phenyl-4H-s-triazolo[4,3-a][1,4]benzodiazepine, melting at 227.5° to 228.5° C. On mixing this with an authentic sample, the melting point of the mixture is not depressed.

B. 8-chloro-1-methyl-6-phenyl-4H-s-triazolo[4,3-a][1,4]benzodiazepine 5-oxide (II).

The third compound eluted from the column in fractions 49 through 70 is mixed with recovered starting material, 8-chloro-1-methyl-6-phenyl-4H-s-triazolo[4,3-a][1,4]benzodiazepine. Fractional crystallization of this mixture from methanol-ethyl acetate gives 0.066 g. of 8-chloro-1-methyl-6-phenyl-4H-s-triazolo[4,3-a][1,4]benzodiazepine 5-oxide (II), melting at 262° to 263° C. (with decomposition). The analytical sample has a melting point of 272.5° to 273.5° C. Infrared spectroscopy supports the proposed structure.

A stirred suspension of 2.94 g. (0.01 mole) of 7-chloro-1-methyl-5-phenyl-s-triazolo[4,3-a]quinoline (prepared as in Part B, above) and 200 ml. of acetone is cooled in an ice bath and treated, dropwise, during a period of about 15 minutes, with a solution prepared from 200 mg. of ruthenium dioxide, 4 g. of sodium periodate and 35 ml. of water. A slight exothermic reaction is noted and the mixture becomes dark. After about 10 minutes, 29 ml. of solution containing 12 g. of sodium periodate in 70 ml. of water is added during about 10 minutes. This mixture is stirred for about 2 hours and then the 41 ml. of remaining sodium periodate solution is added during the next 3 hours. The mixture is allowed to remain at 4° for 18 hours and is concentrated in vacuo to remove acetone. The resulting aqueous mixture is extracted with methylene chloride. The extract is washed with water, dried over anhydrous magnesium sulfate, and concentrated. The residue is chromatographed on 150 g. of silica gel with 2 percent methanol-98 percent chloroform; 60 ml. fractions are collected. Recovered starting material is eluted in fractions 11-14 and crystallized from methanol-methylene chloride to give 0.069 g. of melting point 251.5° to 253.5° C. A mixture of the two products (C and D) is eluted in fractions 15-39. Crystallization of this mixture from ethyl acetate gives 618 mg. (20.8 percent) of 5-chloro-2-(3-methyl-4H-1,2,4-triazol-4-yl)benzophenone (D) of melting point 165.5° to 168° C. Crystallization of the mother liquor from methanol gives 0.126 g., melting point 108-112 and 0.588 g. of melting point 101.5° to 105.5° C. (decomposition) (19.9 percent yield) of a methanol solvate of 4-(2-benzoyl-4-chlorophenyl)-5-methyl-4H-1,2,4-triazole-3-carboxaldehyde (C). The analytical sample has a melting point of 100° to 101.5° C.
